CLAIM

The ornamental design for a vehicle wheel center component, as shown and described.

DESCRIPTION

FIG. 1 is a right front perspective view of my vehicle wheel center component.

FIG. 2 is a front elevational view of my vehicle wheel center component.

FIG. 3 is a sectional view taken along line 3—3 in FIG. 2.

FIG. 4 is a sectional view taken along line 4—4 in FIG. 2.

FIG. 5 is a sectional view taken along line 5—5 in FIG. 2.

The broken lines in the drawing are for illustrative purposes only and form no part of the claimed design.

—FIG. 1

FIG. 2

FIG. 3

FIG. 4

FIG. 5
